FEEDING APPARATUS

Charles E. Kerr, St. Petersburg, Fla., assignor to FMC Corporation, a corporation of Delaware
Original application July 23, 1958, Ser. No. 750,420, now Patent No. 3,016,807, dated Jan. 16, 1962. Divided and this application Mar. 31, 1961, Ser. No. 99,774
11 Claims. (Cl. 221—225)

This application is a division of my copending application Serial No. 750,420, filed July 23, 1958 and entitled "Carton Handling Machine," now Patent No. 3,016,807.

This invention relates to carton handling machines and more particularly to automatic machines for feeding cartons in a folded condition to a carton closing and erecting mechanism.

An object of the invention is to provide an improved carton feeding machine.

Another object of the invention is to provide a machine that receives a supply of cartons in a folded or collapsed condition and feeds them successively to a carton erecting mechanism.

Another object is to provide a carton handling machine of the character described that is completely automatic and which is capable of fully dependable, high speed operation.

Another object is to provide an improved mechanism for withdrawing flat, folded cartons successively from a supply of the same within a storage magazine.

Another object is to provide an improved gate mechanism for a folded carton storage magazine that facilitates the removal of the cartons singly from the magazine.

Other objects and advantages of the invention will become apparent from the following description and the accompanying drawings, in which:

FIG. 1 is a plan of the carton handling machine incorporating the feeding apparatus of the invention.

FIGS. 2A and 2B are enlarged fragmentary elevations which, when assembled end to end, together form a side elevation of the carton handling machine of FIG. 1.

FIGS. 3A and 3B are fragmentary sections which, when assembled end to end, together form a longitudinal, vertical section of the carton handling machine.

FIG. 4 is an enlarged section of part of the mechanism for discharging cartons singly from the supply magazine, taken along lines 4—4 of FIG. 3A.

FIG. 5 is a section along lines 5—5 of FIG. 4.

FIG. 6 is an enlarged elevation of the carton releasing gate of the storage magazine, viewed as indicated by the lines 6—6 of FIG. 3A.

FIG. 7 is a vertical section along lines 7—7 of FIG. 6.

The present invention is adaptable by dimensional modification, and possibly other minor re-design that does not constitute departure from the operational principles involved, to operate upon cartons of different kinds. A typical example of the cartons that can be handled by a machine incorporating the principles of the present invention are the large cartons in which a number of small cartons, usually a dozen or a multiple of a dozen, are commonly enclosed for shipment and for sale in wholesale quantities, or in which a number of cans of milk, fruit, vegetables, pet food, or the like, are handled. Such cartons are characterized by a body portion of rectangular, tubular form, dimensioned to contain a number of cans, boxes or other packages, and a top flap and a bottom flap hinged along fold lines to the upper and lower edges, respectively, of each of the four walls of the body portion. These cartons, commonly called "shipping cases," usually are constructed of heavy paperboard and are received from the manufacturer in a flattened, or folded condition with one end wall and one side wall in planar alignment with each other and superimposed upon

2

the other side wall and the other end wall, respectively, which likewise are in planar alignment with each other. When so folded, the top and bottom closure flaps project from their respective side and end walls in planar alignment therewith.

Described in general terms, the carton handling machine with which the feeding mechanism of the invention is associated includes a supply magazine A (FIGS. 1, 2A, and 3A) adapted to receive and store a number of cartons in the above-described flat, folded condition and in superimposed relation. The cartons are withdrawn one at a time from the bottom of the stack within the magazine A with the aid of a presser mechanism B and a gate mechanism C (FIGS. 1 and 3A) that cooperate with a first conveyor D (FIGS. 1, 2A and 3A) to deliver the folded cartons successively to a second, or main conveyor E (FIGS. 1, 3A and 3B). The two conveyors cooperate with each other in initiating the operation of opening, or unfolding, each carton. This operation occurs at an opening station F adjacent the receiving end of the main conveyor E.

When unfolded, the carton is carried toward the rear of the machine by the conveyor E with the side walls of the carton disposed horizontally and the end walls vertically, one of the end walls being in the lead so that the longitudinal axis of the carton is parallel to its direction of advance. The closure flaps project laterally from the body of the carton, each still in planar alignment with its respective side or end wall, as the case might be. Each carton is propelled in this position to and through a closure flap manipulating station G (FIGS. 1, 2B, and 3B) where the four flaps at one side of the carton, say the side which is destined to become the bottom, are folded inward to, or nearly to, their closing position. Likewise at the manipulating station G, the vertically disposed end wall flaps at the opposite side of the carton are folded outward so that when the carton reaches a position of alignment with a case loading machine H (FIG. 1) the carton can, without interference from the flaps, be shifted laterally of the conveyor by a pusher mechanism J (FIGS. 1 and 2B) to dispose the delivery chute of the case loader within the thus opened side of the carton. The loaded carton is returned to position for advancement on the conveyor E, by the continued action of the case loader in pushing into the carton a charge of the articles to be encased therein; and the filled carton is carried to a tipping mechanism K (FIGS. 1, 2B, and 3B) which operates to tip the carton in a manner disposing it right side up and to place it upon a take-away conveyor L (FIG. 1) or other means for disposing of the filled carton.

Referring now to FIGS. 1, 2A, 2B, 3A and 3B all components of the carton handling machine are mounted upon a frame 30 including two horizontally extending side bars 32 of rectangular cross section (FIG. 1) supported on legs 34 and held rigidly in spaced, parallel relation by transverse bars 36 (FIGS. 1, 3A, 3B), at least two of which preferably interconnect two opposed legs 34 at points somewhat below the level of the side bars 32 thus leaving between the side bars 32 suitable working clearance for certain operative parts of the machine, the details of which are not important to the present invention. An extension 38 of the frame 30 includes two channel members 40 (FIGS. 2B and 3B) secured to and projecting rearward from two of the transverse bars 36 (FIGS. 3A and 3B) and supported at their rear ends by a pedestal 42 (FIGS. 2B and 3B) whose lower end is rigidly secured to a foot plate 44.

The Supply Magazine A

The magazine A (FIGS. 1, 2A, and 3A) is mounted upon the forward end of the frame 30 and includes a

longitudinally slotted bottom plate 50 and front and rear walls 52 and 54, respectively, each of which is provided with flanges 56 projecting inward from its lateral edges. The magazine A is supported by two spaced brackets 58 (FIG. 2A) and 58a (FIG. 3A) secured to the bottom plate 50 and projecting rearward therefrom for engagement upon a shaft 60 (FIG. 3A) that extends rotatably through the two brackets 58 and 58a. The shaft 60 is journaled at its ends in bearings 62 (one of which is shown in FIG. 2A), each of which is mounted on one of the side bars 32 of the frame 30. Thus the supply magazine A is mounted for pivotal adjustment about the transverse shaft 60. The magazine A is adapted to be rigidly secured in position sloping downward and rearward at selected slope, by means of a pair of supporting straps 64 (FIG. 2A) and 64a (FIG. 3A) each of which is pivotally connected at its upper end to the magazine bottom plate 50 and both of which are adjustably connected to one of the transverse bars 36 of the frame 30 by bolts 66 extending through the bar 36 and through vertically elongate slots 68 in the straps 64 and 64a, respectively, adjacent their lower ends.

A second shaft 70 (FIGS. 2A and 3A) is mounted adjacent the end of the magazine bottom plate 50 that is opposite the shaft 60. The shaft 70 is mounted for adjustment longitudinally of the bottom plate 50 by means of bearings 72 (one shown in FIG. 2A) each of which is slidable in a slot 74 (FIG. 2A) in a bracket 76, and both brackets 76 are secured to the plate 50 so that the shaft 70 is spaced the same distance below the magazine bottom plate 50 as is the shaft 60.

Midway between the two lateral sides of the bottom plate 50 and in alignment with the longitudinal slot 78 thereof are sprockets 80 and 82 (FIG. 3A) mounted on the shafts 60 and 70, respectively. Since the sprocket 82 is the driving sprocket of the conveyor D, it is rigidly secured to the shaft 70. However, since the sprocket 80 is merely an idler sprocket it can be mounted to rotate freely upon the shaft 60. A conveyor chain 84 is trained around the two sprockets 80 and 82, the parts being so proportioned and arranged that the upper run of the conveyor chain 84 lies within the slot 78 (FIG. 5) of the magazine bottom plate where it is slidably supported in substantially rectilinear configuration by a channel member 86 bridging the slot 78 and thus interconnecting the two halves of the bottom plate 50. Preferably, the channel member 86 is of relatively heavy construction and is provided with coplanar flanges 88 that extend substantially to the outer lateral edges of the bottom plate 50 so as to provide suitable stiffening reinforcement for the same.

Each of the bearings 72 in which the shaft 70 is mounted is provided with an adjusting screw 89 associated therewith in the well known manner, so that the chain 84 can be properly tensioned.

Pusher lugs 90 are provided on the conveyor chain 84 at suitable intervals throughout the length thereof. As each pusher lug 90 is advanced longitudinally of the slot 78 in the magazine bottom its upper end projects above the level of the magazine bottom 50, the distance that it so projects being substantially equal to the thickness of one of the cartons in its flat, folded condition. The leading end of each pusher lug 90 is formed with a notch 92 therein (FIGS. 3A and 4), within which the trailing edge of a folded carton is adapted to seat while the lug propels the carton out from under the stack of cartons within the magazine A.

The conveyor chain 84 is adapted to be driven so as to move the pusher lug 90 thereof rearwardly of the machine, by a motor 94 having a suitable speed reduction unit (not shown). A driving sprocket (not shown) on the output shaft (not shown) of said speed reduction unit is connected by a drive chain 98 to a sprocket 100 (FIG. 3A) on a countershaft 102 journaled in suitable bearings 104 (FIG. 2A) on the frame side bars 32 adjacent their

forward ends. The countershaft 102 is likewise provided with a sprocket 106 that is connected by a chain 108 to a driven sprocket 110 on the shaft 70 of the conveyor D.

The Presser Mechanism B

As shown in FIGS. 1, 2A, and 3A, the presser mechanism B is mounted partly on the front wall 52 of the magazine A and partly upon the end of the magazine bottom 50 that projects forward beyond the front wall 52. The part of the presser mechanism B that is mounted upon the magazine wall 52 includes an elongate block 120 that is mounted for vertical, longitudinally reciprocatory movement on the outer or forward face of the front wall 52 of the magazine at the lowermost end thereof by means of two vertically aligned straps 122, as best shown in FIGS. 4 and 5. A finger 124 (FIGS. 3A, 4 and 5) is mounted by a pivot pin 126 for pivotal movement within a groove 128 that is machined in the rear face of the block 120.

The pivot pin 126 is intermediate the upper and lower ends of the finger 124, and the finger 124 is constantly urged to rotate counterclockwise as viewed in FIG. 3A by means of a spring 130 (FIGS. 3A and 5) under compression between the front face of the block 120 and one of two cooperating jam nuts 132 screwed onto a threaded rod 134 that extends through the spring 130 and is engaged with the upper end of the finger 124. In this manner, the lower end of the finger 124 is constantly, but yieldably, urged rearwardly of the machine, through a vertical slot 136 in the magazine front wall 52.

The lower end of the finger 124 is formed with a tapered presser foot 138 having a flat under surface and an upper surface so inclined that when the block 120 is slid upward, the sloping upper surface of the presser foot 138 engages the forward ends of those folded cartons at the bottom of the magazine A in a manner causing the presser foot 138 to be cammed forward, i.e., to a position where the presser foot will slide past the edge of each folded carton without exerting any lifting effect thereupon, similarly to the manner in which a ratchet tooth operates. However, upon clearing each carton as the block 120 moves upward, the presser foot 138 is forced rearwardly again by the spring 130 so that when the block 120 moves downward, the flat under surface of the presser foot will engage upon the upper surface of the folded carton therebelow and cause the corresponding region of that carton, as well as the corresponding regions of any cartons below the one engaged by the presser foot, to be pressed downward firmly so as to enhance the security with which the lowermost carton in the stack will be engaged by the next pusher lug 90 to pass under the wall 52 of the magazine.

The part of the presser mechanism B that is mounted upon the magazine bottom plate 50 includes a pair of brackets 140 (FIGS. 1, 2A, and 3A) upstanding from the bottom plate 50 and carrying a short, transversely extending shaft 142 (FIGS. 2A and 3A). Carried by the shaft 142 for pivotal movement about the axis thereof is an operating lever 144 including a rearwardly projecting rod 146 and a forwardly and downwardly inclined sector plate 148 that is rigid with the rod 146. Pivotedly mounted on the shaft 142 is an arm 150 that is adapted to be rigidly secured to the operating lever 144 by a bolt 152 screwed into the arm 150 and extending through a clearance slot 154 in the sector plate 148. The slot is arcuate about a center lying within the axis of the shaft 142. The arm 150 is of such length that a cam follower roller 156 (FIG. 3A) rotatably mounted upon its lower end is adapted to be engaged by a cam 158 rigid with the conveyor drive shaft 70.

The parts are so proportioned and arranged that just before a pusher lug 90 passes rearwardly under the front wall 52 of the magazine, the high lobe of the cam 158 engages the roller 156 causing the operating lever 144 to turn clockwise (FIG. 3A) about the axis of the shaft

142 and thus pushing the block 120 downward. The connection between the operating lever 146 and the block 120 includes a rod 160 (FIGS. 4 and 5) that is vertically reciprocable within a bore 162 within the block 120 and having a socket 163 in its lower end. The upper end of a coil spring 164 is seated within the socket 163 while the lower end of the spring 164 bears against a plug 166 firmly secured to the block 120 within the lower end of the bore 162. Thus, the spring 164 constantly resists downward motion of the rod 160 relative to the block 120.

The rear end 167 of the rod 146 is rounded and extends through a slot 168 in the forward face of the block 120 and is seated within a diametrical slot 169 in the rod 160. Thus, when the operating lever 144 is turned clockwise as hereinabove described, the block 120 is forced downward, carrying with it the finger 124 until the presser foot 138 encounters a carton and compresses the same with a force determined by the strength of the spring 164, after which the block 120 can continue to move downward as determined by the height of the lobe of the cam 158 without exerting any pressure upon the compressed carton, or cartons, as the case might be, in excess of the strength of the spring 164.

The cam follower roller 156 is held against the cam 158, thus causing the block 120 to rise when the lobe of the cam 158 turns out of engagement with the roller 156, by a spring 170 under compression between the rod 146 and a washer suitably immobilized on a rod 172 extending rigidly upward from the magazine bottom plate 50 and axially through the spring 170.

Gate Mechanism C

As hereinabove mentioned, the function of the gate mechanism C is to release one carton, and only one, at a time, so that the folded cartons can be successively propelled from the magazine A onto the main conveyor E. For this purpose, the gate mechanism C is mounted partly upon the rear wall 54 of the magazine A and partly upon the underside of the channel member 86 of the bottom plate 50, immediately below the magazine wall 54. Each carton being propelled rearwardly of the machine by a pusher lug 90 of the conveyor 84 must pass between these two parts of the gate mechanism C.

The part of the gate mechanism C that is mounted upon the magazine wall 54 includes two gauge bars 180. Each of the gauge bars 180 (FIGS. 3A, 6 and 7) is of L-shaped configuration including a stem 182 slidably mounted upon the inner surface of the magazine wall 54 and a foot portion 184 extending below the lower edge of the wall 54, as shown in FIGS. 3A and 7. The stem 182 of each gauge bar 180 is slidably mounted for reciprocatory movement toward and away from the magazine bottom plate 50 by means of shoulder screws 186 (FIGS. 3A, 6 and 7) that extend slidably through vertically elongate slots 188 in the magazine wall 54 and are screwed tightly against the stem 182 of the associated gauge bar 180.

Welded or otherwise rigidly secured to the outer face of the magazine wall 54 is an angle bracket 190 in operative association with each of the gauge bars 180. A guide rod 192 extends slidably through the leg of the angle bracket 190 that projects outward from the wall 54. The lower end of the guide rod 192 is secured to the foot portion 184 of the associated gauge bar and a coil spring 194 encircling the rod 192 and under compression between the bracket 190 and the foot portion 184 constantly urges the gauge bar 180 downward to the limit of its downward movement as determined by the adjustment of a pair of cooperating jam nuts 196 screwed onto the upper end of the guide rod 192. When both sets of the nuts 196 are properly adjusted they hold the foot portions 184 of the gauge bars 180 in such an elevation above the magazine bottom plate 50 that one folded carton can pass freely under the same but more than one can not.

The part of the gate mechanism C that is mounted on the channel member 86 is a leaf spring 200 disposed di-

rectly below each foot portion 184. Both leaf springs 200 are secured to the channel member 86 of the bottom plate 50. Each leaf spring 200 includes a relatively long base section 202 (FIGS. 3A and 7) secured to the under surface of the channel member 86, a substantially vertical portion rising from the after end of the base section 202, and an upper portion 204 extending rearward from the vertical riser portion. As best shown in FIG. 7, the after end 206 of the upper portion 204 is deflected upward so as to engage the corresponding end of the associated foot 184. Moreover, the upwardly inclined end 206 extends upward and rearward beyond the end of the foot 184 where it is curved to provide a rounded shoulder over which a carton can slide without harm to the carton.

The parts are so proportioned and arranged that the forward part of the upper portion 204 of each leaf spring is parallel to the associated foot 184 and is spaced therefrom a distance substantially equal to the thickness of a folded carton, thus providing a space adapted to receive the leading edge of a folded carton when the same is carried rearward by one of the pusher lugs 90. When the leading edge of the carton engages the inclined portions 206 of the leaf springs 200 the springs are deflected downward, permitting the carton to pass between the springs and the foot portions 184 of the gauge bars. However, the leaf springs 200 exert such frictional resistance to such movement of the carton as to insure that the carton is in firm contact with the pusher lug when the carton is discharged from the magazine A. This assures accurate timing of carton release.

When the trailing edge of a carton thus being propelled out from under a stack of cartons within the magazine A passes the terminal ends of the foot portion 184 of the gauge bars 180, the trailing edge of the carton is snapped vigorously upward by the projecting after ends of the leaf springs 200, thus insuring prompt and accurately timed release of the folded carton from the pusher lug.

The Main Conveyor E

The main conveyor E comprises a pair of endless chains 210 (FIGS. 1, 2A, 2B, 3A, 3B) each of which is trained around three sprockets 212, 214, and 216, respectively (FIGS. 3A and 3B). The sprockets 212 (one of which is shown in FIG. 3A) are driving sprockets for the respective chains 210, being secured to a lower countershaft 218 which is driven by a chain 220 trained around a driven sprocket (not shown) rigid with the countershaft 218 and around a second sprocket (not shown) secured to the hereinbefore mentioned output shaft of the speed reduction unit associated with the motor 94. The sprockets 214 (FIGS. 2A and 3A) are driven sprockets that impart rotation to an upper countershaft 224 to which they are rigidly secured. The sprockets 216 are idler sprockets carried by a shaft 225 (FIGS. 1, 2B, and 3B) journaled in bearings 226 (FIG. 2B) slidably mounted in slots 227 in the channel members 40 of the frame extension 38 at the rear end of the machine. Adjusting screws 228 are associated with the bearings 226 in the well known manner to properly tension the conveyor chains 210.

Parallel rails 230 and 230a (FIGS. 1, 2B, 3A and 3B) slidably support the cartons as they progress through the opening station F and the flap manipulating station G. The rail 230 extends clear to the rear end of the machine, but the rail 230a is considerably shorter, terminating at a point that causes each carton to slide off the rear end of the rail 230a as the carton comes into alignment with the case loader H. The chains 210 are each provided with laterally projecting rollers 232 (FIG. 2A), and while the part of either chain to which any one of the rollers is attached is in the upper run of the chain, that roller is supported upon the upper flange 234 of the associated channel member 40, and is prevented from being raised therefrom by the horizontal flange 236 of an angle bar

238. The angle bars 238 and the rails 230 and 230a are supported upon the channel members 40.

Each chain 210 is provided with a plurality of carton erecting and propelling fingers 240, each of which is transversely aligned with a companion finger 240 on the opposite chain 210. Each finger 240 is rigidly secured to one of the links of the associated chain 210 in such a position that throughout the time that the link is within the upper run of the chain the finger projects vertically upward therefrom. Each finger 240 has a bar 242 pivoted at one end thereto and projecting rearwardly therefrom, i.e., in the direction opposite to the direction in which the finger advances when the conveyor E is in operation. The pivoted end of each bar 242 is loosely seated within a notch 244 in a lateral side of the associated finger 240, the arrangement being such that when the part of the associated chain on which the finger is mounted is in the upper, rearwardly moving run of the chain the bar 242 rests against one side of the associated notch 244 and is held thereby in a position projecting substantially horizontally rearward from the finger, but after passing around the associated sprocket 216 the bar 242 is free to pivot under the influence of gravity to a position of oblique angularity with the finger as shown in the lower portion of FIGS. 2B and 3B. The erecting and propelling fingers 240 are so spaced apart on their chains 210 that the distance between each finger 240 and the trailing end of the bar 242 of the preceding finger 240 is equal to the longitudinal dimension of one of the cartons after the carton has been erected by the machine. Thus, each finger and the bar 242 of the preceding finger cooperate to define a carton receiving pocket on the conveyor E within which an erected carton can be propelled by the conveyor toward the rear of the machine.

In the opening or erecting station F of the machine, the lower portion of each carton is kept in proper alignment by longitudinally extending guides 246 (FIGS. 3A and 3B) which are adjustably mounted on the machine frame 30 by supporting rods 248 (FIG. 1). A pair of overhead endless chains 250 (FIGS. 1, 2A, 2B, 3A and 3B) cooperate with the fingers 240 and bars 242 in guiding and propelling the cartons through the machine. Each of the overhead chains 250 is trained around longitudinally spaced sprockets 252 and 254, respectively, carried by shafts 256 and 258, respectively. The two shafts 256 and 258 are suitably journaled in bearings 260 and 262, respectively (FIGS. 3A and 3B). The bearing 260 is mounted in fixed position at one end of a tubular brace bar 264 of rectangular cross section while the bearing 262 is slidably mounted within the opposite end of the brace bar and is provided with an adjusting screw 265 in association therewith in the well known manner to enable the overhead chains 250 to be properly tensioned.

Each of the overhead chains 250 is provided with upstanding pusher lugs 266 spaced apart thereon distances equal to the spacing between each erecting finger 240 and the trailing end of the preceding bar 242. Moreover, each pusher lug 266 on either overhead chain 250 is transversely aligned with a companion pusher lug on the other overhead chain 250 and the conveyor chains 210 and 250 are so related to each other that when the parts of the overhead chains 250 by which a pair of pusher lugs 266 are carried are in the lower runs of the chains 250, the leading edges of that pair of lugs 266 are in planar alignment with the leading edges of a pair of erecting and propelling fingers 240 immediately therebelow.

The overhead chains 250 are mounted at such height above the main conveyor E that the lower runs of the chains 250 rest upon the upper surface of an erected carton on the conveyor E and thereby aid in holding the carton in position upon the conveyor E.

The supporting means for the overhead chains 250 includes a pair of longitudinally extending plates 268. Each plate 268 carries a bearing 270 (FIGS. 1 and 2A) at its rear end and the shaft 256 is journaled in the two

bearings 270. Each plate 268 is rigidly but adjustably mounted at its forward end on a bracket 272 rigidly secured to and extending upward from a side bar 32 of the frame 30. The after end of the brace bar 264 rests upon an arm 274, the outboard end of which is rigidly secured to a post 276 extending rigidly upward from a side bar 32 of the frame 30. The arm 274 extends inward from the post 276 and just above the lower run of one of the chains 250 (FIG. 2B) so that the portion of the brace bar 264 adjacent its rear end can rest upon the inboard end of the arm 274.

The overhead chains 250 are driven by a chain 278 (FIGS. 1 and 2A) trained around a sprocket 280 (FIG. 2A) rigid with the countershaft 102 and around a sprocket 282 (FIG. 3A) rigid with a sleeve (not shown) that is rotatable upon a stub shaft 286 carried by one of the plates 268. The sleeve also has a reversing gear (not shown) secured thereto which is enmeshed with a gear 290 (FIG. 1) on the shaft 256 of the overhead chains 250. The ratios of the several gears involved in the drive for the overhead chains 250 are such that the linear speed of the chains 250 is the same as that of the chains 210; and in view of the presence of the reversing gear in this drive, the lower runs of the chains 250 move in the same direction as the upper runs of the chains 210.

Operation

Whereas the manner of operation of each of the constituent parts of the carton feeding mechanism of the invention has been explained hereinabove in connection with the description of the construction thereof, understanding the operation of the mechanism may be facilitated by the following description of the feeding of a single carton therefrom.

It will be assumed that the motor 94 is in operation. When a pusher lug 90 of the supply magazine conveyor D passes under the front wall 52 of the magazine A the lowermost carton will engage within the notch 92 of that pusher lug, such engagement being facilitated and made more positive by the action of the presser mechanism B, as hereinabove explained. A single folded carton is, therefore, propelled out from under the remainder of the stack of cartons within the magazine A between the gauge bars 180 and the springs 200, which are effective in preventing more than one carton from leaving the magazine A at a time, and delivered to the carton opening station F.

While a particular embodiment of the present invention has been shown and described it will be understood that the apparatus is capable of modification and variation without departing from the principles of the invention and that the scope of the invention should be limited only by the scope and proper interpretation of the claims appended hereto.

The invention having thus been described, what is believed to be new and desired to be protected by Letters Patent is:

1. In a carton handling machine, feeding apparatus comprising a magazine adapted to contain a stack of collapsed cartons and including a longitudinally slotted bottom, a chain extending longitudinally of the slot in said magazine bottom, means for driving said chain, a pusher lug projecting upward from the chain beyond the plane of the upper surface of the magazine bottom to engage the lowermost carton in said stack, presser means vertically reciprocable within said magazine and engageable with one of the collapsed cartons therein to press the same downward and thereby retain said lowermost carton in position for engagement by said pusher lug, and drive means for reciprocating said presser means.

2. In a carton handling machine, feeding apparatus comprising a magazine adapted to contain a stack of collapsed cartons and including a longitudinally slotted bottom, a chain extending longitudinally of the slot in said magazine bottom, means for driving said chain, a pusher lug projecting upward from the chain beyond the plane of the upper surface of the magazine bottom

to engage the lowermost carton in said stack, presser means vertically reciprocable within said magazine and engageable with one of the collapsed cartons therein to press the same downward and thereby retain said lowermost carton in position for engagement by said pusher lug, and means for reciprocating said presser means in timed relation with said chain driving means.

3. In a carton handling machine, feeding apparatus comprising a magazine adapted to contain a stack of collapsed cartons and including a longitudinally slotted bottom and a wall extending upward therefrom, a pusher lug projecting upward through said slot, means for moving the pusher lug along the slot, presser means mounted on said wall for vertical reciprocation and for horizontal movement, yieldable means urging said presser means inwardly of the magazine to a position for engagement with one of the collapsed cartons, and means for vertically reciprocating said presser means, said reciprocating means being operative to move the presser means downward as the pusher lug passes under said wall to press the lowermost carton against the magazine bottom and positively into position to be engaged by said pusher lug.

4. In a carton handling machine, feeding apparatus comprising a magazine adapted to contain a stack of collapsed cartons and including a longitudinally slotted bottom and a wall extending upward therefrom, a pusher lug projecting upward through said slot, means for moving the pusher lug along the slot, a presser foot mounted on said wall for vertical reciprocation and for horizontal movement, said presser foot having a substantially horizontal carton engaging undersurface and an upper, camming surface sloping downward and inward of the magazine to the inner end of the presser foot, said camming surface being engageable with an edge of a collapsed carton to cam the presser foot outwardly of the magazine to clear the carton engaged thereby as the presser foot moves upward, yieldable means urging said presser foot inwardly of the magazine to a position for engagement with one of the collapsed cartons as the presser foot moves downward, and means for vertically reciprocating said presser foot, said reciprocating means being operative to move the presser foot downward as the pusher lug passes under said wall to press the lowermost carton against the magazine bottom and positively into position to be engaged by said pusher lug.

5. In a carton handling machine, feeding apparatus comprising a magazine adapted to contain a stack of collapsed cartons, a pusher lug projecting into the magazine in position to engage a carton in said stack, means for moving said pusher lug to propel a carton engaged thereby out of the magazine, and resilient gripping means disposed on opposite sides of the path of movement of the lug for slidably engaging the underside of a carton being propelled out of said magazine to resist movement thereof and thereby maintain the carton in engagement with the pusher lug.

6. In a carton handling machine, feeding apparatus comprising a magazine adapted to contain a stack of collapsed cartons and including a longitudinally slotted bottom and a wall extending upward therefrom, a chain extending longitudinally of said slot in the magazine bottom, means for driving said chain, a pusher lug projecting upward from the chain beyond the plane of the upper surface of the magazine bottom to engage the lowermost carton in said stack and propel the same outward from under the remainder of the stack and under said wall, and resilient gripping means for slidably engaging the underside of a carton being propelled under said wall to cooperate with said wall to resist movement of the carton and thereby maintain engagement of said pusher lug therewith.

7. In a carton handling machine, feeding apparatus comprising a magazine adapted to contain a stack of collapsed cartons and having a laterally opening discharge slot therein, a pusher lug projecting into the maga-

zine in position to engage a predetermined number of cartons in said stack, means for moving said pusher lug to propel said predetermined number of cartons engaged thereby out of the magazine through said discharge slot, 5 a gauge bar mounted on said magazine adjacent said discharge slot in position to limit to said predetermined number the number of collapsed cartons that can pass through said slot at a time, and a resilient strip mounted at its inner end on said magazine and projecting parallel 10 to said gauge bar at a distance therefrom corresponding substantially to the thickness of said predetermined number of collapsed cartons, the outer end of said resilient strip being inclined outwardly of the magazine and toward said gauge bar to slidably engage the underside 15 of a carton being propelled out of said magazine to cooperate with said gauge bar to resist movement of said carton and thereby maintain the carton in engagement with the pusher lug.

8. In a carton handling machine, feeding apparatus 20 comprising a magazine adapted to contain a stack of collapsed cartons and having a laterally opening discharge slot therein, a pusher lug projecting into the magazine in position to engage a carton in said stack and having a notch in its front face within which an edge of the carton seats, means for moving said pusher lug to 25 propel the carton out of the magazine through said discharge slot, a gauge bar mounted on said magazine adjacent said discharge slot in position to block passage of all but said one collapsed carton from passage through said slot, and a resilient strip mounted at its inner end 30 on said magazine and projecting below said gauge bar at a distance therefrom corresponding substantially to the thickness of one of the collapsed cartons, the outer end of said resilient strip being inclined outwardly of the 35 magazine and upward to slidably engage the underside of a carton being propelled out of said magazine to cooperate with said gauge bar to resist movement of said carton and thereby maintain the carton in engagement with the pusher arm with an edge of the carton seated in said notch, said outer end of the resilient strip projecting upward beyond the gauge bar to snap said edge of the carton out of said notch when the edge passes beyond the gauge bar.

9. In a carton handling machine, feeding apparatus 45 comprising a magazine adapted to contain a stack of collapsed cartons, a chain extending longitudinally of and beneath the said magazine, means for driving said chain, a pusher lug projecting upward from the chain to engage the lowermost carton in said stack, presser means 50 positioned adjacent the lowermost edge of said stack and being vertically reciprocable within said magazine and engageable with one of the collapsed cartons at the said lowermost edge of the stack to press the same downward and thereby retain said lowermost carton in position for 55 engagement by said pusher lug, and means for reciprocating said presser means to cause it to successively engage different ones of the cartons at the lowermost edge of the magazine as cartons are removed therefrom by said pusher lug.

60 10. In a carton handling machine, feeding apparatus comprising a magazine adapted to contain a stack of collapsed cartons, continuous conveying means extending across one end of said magazine, means for continuously driving said conveying means, a pusher lug projecting 65 from said conveying means in a direction to engage the endmost carton in said stack, presser means positioned adjacent said end of said magazine and being mounted for reciprocable movement along the direction of said stack and being engageable with one of the collapsed cartons in said stack near said conveying means to compress the same and thereby retain said endmost carton in a compressed position for immediate engagement by said pusher lug, means for reciprocating said presser means to cause it to successively engage different ones 70 of the collapsed cartons in the stack near said conveying 75

means as cartons are removed therefrom by said pusher lug, and resilient means associated with said presser means to urge said presser means inwardly of said magazine and between adjacent collapsed cartons and to allow said presser means to move past a collapsed carton as it is reciprocated away from said conveying means.

11. In a carton feed mechanism of the type in which a pusher lug moves through an opening in an end of a carton supply housing to engage the endmost collapsed carton at the bottom of a stack of cartons in the housing and to push the engaged carton out of the housing, the improvement which comprises a carton presser mechanism having a portion movable downwardly and inwardly of

5 said housing between adjacent collapsed cartons to engage one of the cartons in said housing near said pusher lug and force it into a compressed position at least partially separated from the cartons in the stack thereabove and whereby said endmost carton in said housing is compressed in the path of movement of said pusher lug.
